UNITED STATES PATENT OFFICE.

STANLEY WOJCIK, OF ORENCO, OREGON.

DESIGN FOR A TOY.

58,054.

Specification for Design.

Patented May 31, 1921.

Application filed April 6, 1921. Serial No. 459,159. Term of patent 7 years.

To all whom it may concern:

Be it known that I, STANLEY WOJCIK, a citizen of Poland, and a resident of Orenco, in the county of Washington and State of Oregon, have invented a new, original, and ornamental Design for a Toy, of which the following is a specification, reference being had to the accompanying drawing, forming part thereof.

The figure is a front view of a toy showing my new design.

I claim—

The ornamental design for a toy as shown.

STANLEY WOJCIK.
